UNITED STATES PATENT OFFICE

FRANK MASTRANGELO AND ALPHONSO MASTRANGELO, OF FITCHBURG,
MASSACHUSETTS

TELEPHONE CABINET

Application filed March 26, 1931. Serial No. 525,542.

This invention relates to cabinets such as cabinets designed for holding a telephone and the general object is to provide a cabinet of this character which is provided with a slide 5 forming the bottom of a compartment and provide a roll top door for this compartment which, when the slide is pulled out, automatically lifts, and which when the slide is pushed in, automatically lowers.

10 A further object is to provide a cabinet of this character which may be built in a wall or form part of a piece of furniture.

Other objects will appear in the course of the following description.

15 Our invention is illustrated in the accompanying drawings, wherein:—

Figure 1 is a front elevation of the cabinet;

Figure 2 is a section on the line 2—2 of Figure 1;

20 Figure 3 is a section on the line 3—3 of Figure 1 but showing the cabinet closed;

Figure 4 is a section on the same line as Figure 3 but showing the cabinet open.

Referring to these drawings, 10 designates 25 the base frame of the cabinet and 11 the side walls projecting from this base frame extending down from a point near the top of this frame 10 nearly to the bottom thereof.

12 designates side walls which extend rearward of the frame 10, there being a back 13 and upper and lower walls 14. The bottom of the front of the cabinet is formed by the wall 15.

30 Sliding in grooves 16 is a slide or shelf 17 having a recess 18 upon which the base of the telephone is adapted to rest. Hinged to the bottom 15 is a door 19, this door being hinged at 20 and having pivotally connected to it the rearwardly and upwardly extending slotted braces 21 through which the screws 22 pass, these braces acting to support the door 19 when it is lowered. The cover or compartment formed beneath the sliding shelf 17 is adapted to hold telephone books 40 or the like.

Extending upward and rearward in a curve is a recess or groove 23 cut into each end wall 11. Each recess extends upward and rearward and then extends downward and rearward as at 24 also in a curve, this

portion 24 of the recess extending downward and terminating at a point rearward of the grooves 16. Disposed within these grooves 23 and 24 is a roll top designated generally 25.

This roll top is composed as usual of relatively small sections 26 glued or otherwise attached to a fabric or flexible backing 27. For the purpose of automatically operating this roll top when the slide 17 is pulled out or

pushed in, I provide levers 28 mounted on 45 each end wall of the cabinet, each lever being in the form of a bell crank pivoted at 29 and each lever at its lower end being connected by a link 30 to a bracket 31 attached to the upper face of the slide 17.

When the slide 17 is pushed home, the lever 28 will swing upward and carry the roll top downward in the grooves 23 until, when the slide 17 is fully pushed home, the roll top will

close against the upper face of the slide, leaving a small portion of the slide projecting 50 which constitutes a handle whereby the slide may be shifted, the slide being preferably formed so as to provide finger holding means

thereon. When the slide is pulled outward, 55 a reverse action takes place, the levers swinging downward and rearward to carry the roll top downward and inward and into the grooved portion 24.

Thus it will be seen that whenever it is desired to use the telephone, 60 it is only necessary to pull outward on the slide 17 whereupon the roll top will raise and permit the telephone to be pulled out

of the cabinet and when the slide is shifted inward carrying the telephone with it, the 65 roll top will close. A more or less ornamental cornice 32 is disposed just above the uppermost portions of the slots 23 with which

the roll top 25 closely approximates so that the telephone is entirely housed and protected 70 when the roll top is closed.

It will be seen that a device of this kind is very simple and convenient, that it entirely protects the telephone when not in use, and

that the cabinet can form a very ornamental 75 part of a room or office. Furthermore, the roll top may be easily locked so as to prevent anyone from having unauthorized access to the telephone. It will be seen that this

device entails no extra work on the user. 80

85

100

He does not have to open the door of the cabinet and then withdraw the telephone, but he simply pulls the shelf 17 toward him which will automatically raise the roll top or push the telephone from him which will automatically close the roll top.

The metallic casing within which the bell and other allied parts are housed may be easily contained within the lower portion of the cabinet so as to be out of sight.

While we have described our invention with special reference to a wall cabinet which is particularly adapted to contain a telephone and be used as a telephone cabinet, we do not wish to be limited to this use nor do we wish to be limited to the particular form of the cabinet as shown. The cabinet as illustrated is a wall cabinet to be built into a wall but the cabinet may form equally well a part of a piece of furniture, as for instance, a desk or book case or the like and the cabinet is applicable for other uses than as a receptacle for a telephone.

We claim:

- 25 1. A cabinet including a compartment having side walls, a back and top, a shelf slidingly mounted between the side walls, the side walls each having a groove extending upward and rearward and then downward, a roll top having its ends disposed in said grooves, bell crank levers mounted upon the side walls of the compartment, each having an arm extending rearwardly and connected to one end of the roll top and having an arm extending downward and operatively connected to the shelf.
- 30 2. A cabinet including a compartment having side walls, a back and top, a shelf slidingly mounted between the side walls, the side walls each having a groove extending upward and rearward and then downward, a roll top having its ends disposed in said grooves, bell crank levers mounted upon the side walls of the compartment, each having an arm extending rearwardly and connected to one end of the roll top and having an arm extending downward, and links pivotally connected to the lower ends of the last named arms and to said shelf.
- 35 3. A cabinet of the character described, comprising a supporting frame, a compartment mounted within said frame and having side walls, a top wall, a rear wall and a bottom wall, the side walls being horizontally grooved, a sliding shelf mounted in said grooves and disposed between the top wall of the compartment and the bottom wall thereof and constituting a support for an article, the side walls of the compartment above said shelf being formed each with a groove, the groove extending upwardly and rearwardly and then downwardly and rearwardly, a roll top having its ends disposed in said grooves, oppositely disposed bell crank levers pivotally mounted upon the side walls and having

their rear ends pivotally connected to the rear end of the roll top, the forward ends of the bell crank levers having linked connection to the shelf whereby as the shelf is pulled outward, the roll top will be shifted upward and then downward into the rear portions of the grooves and as the shelf is pulled inward the roll top will be shifted upward and then downward into the forward portions of said grooves and close against the shelf.

In testimony whereof we hereunto affix our signatures.

FRANK MASTRANGELO.

ALPHONSO MASTRANGELO.
